CLAIM

The ornamental design for a ceiling fan, as shown and described.

DESCRIPTION

FIG. 1 is a top perspective view of a ceiling fan showing our invention;

FIG. 2 is a bottom perspective view of the ceiling fan of FIG. 1;

FIG. 3 is a top elevation view of the ceiling fan of FIG. 1; FIG. 4 is a bottom elevation view of the ceiling fan of FIG. 1;

FIG. 5 is a front side view of the ceiling fan of FIG. 1; FIG. 6 is a back side view of the ceiling fan of FIG. 1; FIG. 7 is a right side view of the ceiling fan of FIG. 1; and, FIG. 8 is a left side view of the blade of FIG. 1.

Portions of the ceiling fan shown in broken lines form no part of the claimed design.

The ceiling fan blade is shown with a symbolic break in its length. The appearance of any portion of the ceiling fan blade between the break lines forms no part of the claimed design.

1 Claim, 8 Drawing Sheets
